UNITED STATES PATENT OFFICE.

JAMES J. HAROLD, OF JERSEY CITY, NEW JERSEY, ASSIGNOR, BY MESNE ASSIGNMENTS, TO EMMA HAROLD, OF JERSEY CITY, NEW JERSEY.

METAL PILING.

No. 807,378.

Specification of Letters Patent.

Patented Dec. 12, 1905.

Application filed August 31, 1904. Serial No. 222,952.

To all whom it may concern:

Be it known that I, JAMES J. HAROLD, a citizen of the United States of America, residing at Jersey City, in the county of Hudson and State of New Jersey, have invented certain new and useful Improvements in Metal Piling, of which the following is a specification, reference being had therein to the accompanying drawings.

10 My invention relates to improvements in metallic piling as used in subway, foundation, and irrigation work, dams, mine-shafts, caissons, sea-walls, locks, coffer-dams, retaining-walls, and similar structures, and comprises 15 flanged beams, preferably the channel-beam type, interlocked by coupling-plates having interlocking strips.

Referring to the accompanying drawings, Figure 1 is an end view of a straight run of 20 my piling, showing the use of channel-beams; and Fig. 2 is a perspective view of the same. Fig. 3 is an end view of a straight run of my piling, showing the use of beams having flanges on one side and interlocking strips on the other 25 side of the same face.

A represents beam members; B, the coupling-plates, and C the interlocking strips engaging the flanges of the beam members. In Fig. 3 it will be observed that one of the 30 flanges of each beam member D is substituted by an interlocking strip, thereby avoiding the use of coupling-plates. Each strip is attached by rivets along one face a short distance from the edge and opens outwardly, thereby firmly 35 locking the flange of the adjoining member.

In construction each member is driven down

in the usual manner, the grooves formed by the strips C being large enough to receive and guide the flanged members into place.

I do not confine my invention to the exact 40 construction shown and described, as modifications may be made without departing from the spirit of the same.

Having described my invention, what I claim as new, and desire to secure by Letters 45 Patent, is—

1. In metal sheet-piling, a beam-section consisting of a flat web-plate and companion locking-angles rigidly mounted thereon, the respective edges of the web-plate extending be- 50 yond the line of the free hook edges of the angles.

2. In metal sheet-piling, a beam-section consisting of a flat web-plate and companion locking-angles rigidly mounted on and located ad- 55 jacent to the respective edges thereof, the bent-around hook edges of said angles being set at angle other than a right angle.

3. In metal sheet-piling, a channel-beam section and a piling-section consisting of a web-plate and companion angles rigidly mounted thereon and provided with hook edges adapted 60 to conform to and interlock with the companion flanges on the channel-beams in assembling the piling-sections in their alternate arrangement.

In testimony whereof I affix my signature in presence of two witnesses.

JAMES J. HAROLD.
